US0D1058216S

(12) **United States Design Patent** (10) **Patent No.:** **US D1,058,216 S**
(45) **Date of Patent:** **** Jan. 21, 2025**

(54) **STORAGE RACK**

(71) Applicant: **ShenZhen YiHong Technology Co., LTD**, Shenzhen (CN)

(72) Inventors: **Chunlong Qiu**, Shenzhen (CN); **Xiao Zhang**, Shenzhen (CN)

(73) Assignee: **ShenZhen YiHong Technology Co., LTD**, Shenzhen (CN)

(**) Term: **15 Years**

(21) Appl. No.: **29/967,778**

(22) Filed: **Oct. 12, 2024**

(51) LOC (15) Cl. **06-06**

(52) U.S. Cl.

USPC **D6/513**

(58) **Field of Classification Search**

(57) **CLAIM**

The ornamental design for a storage rack, as shown and described.

DESCRIPTION

FIG. 1 is a front, right and top perspective view of a storage rack showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, right and top perspective view of the storage rack in a use state.

The broken lines depict portions of the storage rack that form no part of the claimed design.

1 Claim, 9 Drawing Sheets
